United States Patent Office.

ONATHAN CRABTREE, OF PHILADELPHIA, PENNSYLVANIA, ASSIGNOR
TO JOHN GAY, OF SAME PLACE.

Design No. 4,253, dated July 19, 1870.

DESIGN FOR A CARPET-PATTERN.

The Schedule referred to in these Letters Patent and making part of the same.

, JONATHAN CRABTREE, of the city of Philadelphia, and State of Pennsylvania, have invented and produced a new and original Design for Carpets, of which the following is a specification.

The nature of my design is fully represented in the accompanying photographic illustration, to which reference is made.

I claim as my invention—
The design for a carpet, as shown.
JONATHAN CRABTREE.
